UNITED STATES PATENT OFFICE.

ALBION W. FOSTER, OF MILLBRIDGE, MAINE, ASSIGNOR OF ONE-HALF TO
JASPER WYMAN, OF SAME PLACE.

DEVICE FOR APPLYING WALL-PAPER.

SPECIFICATION forming part of Letters Patent No. 630,678, dated August 8, 1899.

Application filed March 29, 1899, Serial No. 710,929. (No model.)

To all whom it may concern:

Be it known that I, ALBION W. FOSTER, of Millbridge, in the county of Washington and State of Maine, have invented a new and Improved Device for Applying Wall-Paper, of which the following is a full, clear, and exact description.

The object of the invention is to so combine a brush and a roller that they may be used to the best advantage in applying paper either to the ceiling or to the side wall of a room and whereby the operator need use but one hand, may match the pattern with accuracy, and may quickly fix the paper upon either a side wall or a ceiling without need of scaffolding and with less labor than heretofore.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in both figures.

Figure 1 is a plan view of the improved device, and Fig. 2 is a side elevation of the same.

The brush A consists, as usual, of a back 10 and bristles 11. The bristles are preferably arranged in a single row of bunches extending from end to end of the back, near the forward or outer longitudinal edge of said back, as shown in Fig. 1; but two or more rows of bunches of bristles may be employed, it being necessary only that the bunches of bristles should be just thick enough to give them the desired spring and have sufficient bearing on the paper to force it gently, yet firmly, in position upon the intended support.

A bracket 12 is secured upon the outer or front longitudinal edge of the brush-back at each of its ends, the side edges of the brackets being usually in the same horizontal plane with the top and bottom surfaces of the brush-back, as shown in Fig. 2. A roller 13 is journaled in the said brackets 12, and the surface of this roller turns about flush with the under face of the brush-back, so that the bristles 11 extend well down beyond said surface 50 of the roller.

A handle B is used in connection with the

brush and its roller, and this handle is telescopic, comprising a skeleton section adapted for attachment to the brush and an inner stick-section. The skeleton section is made of stout wire bent upon itself to form a transverse downwardly-extending yoke 14, two parallel side members 15, and attaching members 16, which extend in opposite directions from the forward ends of the side members. These diverging or fastening members 16 of the skeleton section of the handle are made to follow the contour of the inner edge of the brush-back, and each of the diverging sections 16 of the handle preferably terminates in a spur, the spurs being driven into the back of the brush, and the said diverging members are further held in engagement with the back of the brush by staples 17 or their equivalents. The stick-section of the brush 70 may be either solid or tubular, and said section is adapted to slide between the side members 15 of the skeleton section in engagement with the concaved or upper surface of the yoke portion 14 of said skeleton section, as 75 shown in Fig. 2.

Guides 18 are attached to the stick-section, through which the side members of the skeleton section pass. These guides are placed at desired intervals and may be in the form of 80 staples, as illustrated. A stop 19 is located upon the under face of the stick-section of the handle, and when the sections of the handle are drawn out to their greatest extent the stop 19 will engage with the outer or 85 rear surface of the yoke 14, locking the sections together. The skeleton section of the handle may slide in grooves in the stick-section, if desired.

In operation the paper is coated with paste 90 in the usual or in any desired manner and after being so coated is taken up and supported at its center by bringing the roller and working surface of the brush-bristles in engagement with the central part of the outer 95 face of the paper. In this manner the paper is carried to the ceiling or side wall and is attached thereto in a manner to match the pattern, and by an upward and downward movement or a movement in direction of 100 either end of the strip of paper the said strip will be firmly and smoothly secured in place

upon the wall or the ceiling. When the device is in operation, the unattached end of the paper falls down over the roller 13. The roller serves to guide the paper to place, while the brush fixes the paper upon the wall or ceiling. The length of the roller 13 preferably corresponds to the width of wall-paper, and said roller may be provided with a scale if in practice it is found desirable.

10 Having thus described my invention, I claim as new and desire to secure by Letters Patent—

15 1. A device for applying wall-paper, consisting of a brush formed of a back and bristles extending from said back, a roller mounted on said back, and a telescopic handle formed of a skeleton section having members attached to the back, parallel side members extending from the back and connected by a
20 yoke, and a stick-section having guides fitted around the side members of the skeleton section and a stop adapted to engage with the

yoke to limit the outward movement of the stick-section, as set forth.

2. In a device for applying wall-paper, the combination, with a brush consisting of a back, and a row of bunches of bristles adjacent to the outer or forward longitudinal edge of said back, brackets secured to the forward or outer longitudinal edge of the brush-back, extending horizontally therefrom, and a roller journaled between said brackets, the bristles of the brush extending beyond the under face of the said roller, of a telescopic handle comprising a skeleton section attached to the brush-back, a stick-section mounted to slide in the skeleton section and having guided connection therewith, and a stop arranged to secure one of the sections relatively to the other, for the purpose specified.

ALBION W. FOSTER.
